UNITED STATES PATENT OFFICE.

SIDNEY B. ANDREWS, OF CHICAGO, ILLINOIS.

IMPROVEMENT IN SPRING BED-BOTTOMS.

Specification forming part of Letters Patent No. 125,250, dated April 2, 1872.

Specification describing a new Suspension Spiral-Wire Spring Bed-Bottom, invented by SIDNEY B. ANDREWS, of the city of Chicago, in Cook county and State of Illinois.

My invention relates to what I term a suspension spiral-wire spring bed-bottom.

In the accompanying drawing, Figure 1 represents a horizontal or face view of my invention as it appears when completed and ready for use. Fig. 2 represents a side elevation, and shows the position of all the parts of my invention except the rings, which appear in Fig. 1. Fig. 3 represents a single spiral spring with its connections when in its proper position in the invention.

My invention consists of five different parts: first, a wooden frame; second, spiral springs; third, rings; fourth, hook-links; and fifth, suspension wires.

In Fig. 1, A is a wooden frame, within which my invention is constructed and suspended. This wooden frame should be made of strips of hard stiff wood, about three inches wide and one and one-half inch thick. In Fig. 1, b represents the spiral-wire springs in a horizontal view, and in the same figure c represents the rings as they appear in a horizontal view in their proper places; and d represents the hook-links, by which the springs and rings are connected in Figs. 1, 2, and 3. In Figs. 1 and 2, e represents the suspension wires, which pass around the frame A and hold the entire combination of springs, rings, and hook-links in suspension in the frame A. The suspension wires e are all held in their proper places on the frame by means of the small wire staples f, which are sunk into the frame A so as to include the suspension wires between the legs or prongs of the staples. This is only intended to prevent the suspension wires from moving laterally on the frame, not to fasten them, as they are intended to have a free perpendicular action at right angles with the frame.

By reference to Fig. 2 it will be seen that my invention presents the same appearance on both sides; there is no upper and under side to it; either side can be used uppermost.

Every part of my invention should be of an exact size—that is to say, all the springs should be of the same size, all the rings should be of the same size, all the hook-links should be of the same size, and all the suspension wires should be of the same length—so that any one of a kind may be used in place of any other one of the same kind.

Care must be taken, in the construction of my invention, that every part—springs, rings, hook-links, and the suspension wires—shall all be tightly connected together in the frame, so that every part may answer the purpose for which it is designed. This being done, every part of my invention will sustain every other part, as they are all closely connected, and any weight or pressure upon any part of it draws equally upon all the other parts.

If, in the construction of my invention, it is desirable to produce a bed-bottom which will sustain greater weight, any number of the rings may be removed and an equal number of springs put in their places; and when less stiffness is desired a few of the springs may be removed and rings substituted.

Having thus described my invention, what I claim as new and as my invention, and desire to secure by Letters Patent, is—

The combination of the several parts of my invention—viz., the springs b, rings c, and links d, with the suspension wire e and frame A—so as to form a suspension bed-bottom, substantially as and for the purposes set forth.

SIDNEY B. ANDREWS.
